Ms. 1080

Apollos Richmond, of Brooklyn, Conn.
Letters Patent No 1080 Dated Feb 1, 1859.

The Schedule referred to in these Letters Patent and making part of the same

To all whom it may concern:

Be it known that I, Apollos Richmond of Brooklyn, in the County of Windham and State of Connecticut, have invented certain new and improved designs for the plates, doors, . . . &c. of Stoves, of which the following is a full clear and exact description, reference being had to the accompanying drawings making part of this specification in which.

Fig. 1. is a front view of a portion of a Cook Stove, similar to that for which letters patent were granted to me September 14th, 1858.

Fig. 2. is a view of one of the end plates, with the oven doors.

Fig. 3. a piece of the cornice or molding round the top of the Stove.

The parts which I consider new and my original designs, are 1st. The plate A. on which the body of the Stove rests, of the general contour and style shown, with its edges molded and beaded, as at a. b.

2nd. The front plate B. with its doors C.D. ornamented with beading e. and an escutcheon d. on each panel.

3rd. The oven plate E. fig. 2. with its doors F.G. with beading and escutcheons substantially similar to those on the plate B.

4th. The form of the cornice or molding H. fig. 3.

5th. The legs I. with beading e. and escutcheon f. as shown.

Claim.

What I claim as my invention and desire to secure by letters patent is.

First. The form and pattern of the plates A.B. &c.

Second. The beadings and escutcheons of the designs shown.

Third. The design of the molding H. The whole forming an ornamental Stove as herein above described.

Witnesses.

End Hingati Hayes.
